— I —. 1

— I —. 4

FIG. 1 is a top plan view of a consultation table having compartments for retaining modular inserts and the like of the present invention.

FIG. 2 is a front or rear elevational view of the consultation table having compartments for retaining modular inserts and the like of FIG. 1.

FIG. 3 is a left or right side elevational view of the consultation table having compartments for retaining modular inserts and the like of FIG. 1.

FIG. 4 is a bottom plan view of the consultation table having compartments for retaining modular inserts and the like of FIG. 1.

FIG. 5 is a perspective view of the consultation table having compartments for retaining modular inserts and the like of FIG. 1, showing the lid portions of two of the table compartments in an open position and showing the center compartment in a rotated position wherein the center compartment has been rotated 180 degrees with respect to the showing of the center compartment in FIGS. 1, 2 and 3.

FIG. 6 is a sectional view of the consultation table having compartments for retaining modular inserts and the like of the present invention, taken substantially along the lines 6-6 of FIG. 5.

I claim:

The ornamental design for a consultation table having compartments for retaining modular inserts and the like, substantially as shown and described.
